UNITED STATES PATENT OFFICE.

WILLIAM BRAMMER, OF HAVERHILL, MASSACHUSETTS.

CEMENT OR ADHESIVE APPLYING DEVICE.

1,361,819.

Specification of Letters Patent. Patented Dec. 14, 1920.

Application filed September 8, 1919. Serial No. 322,380.

To all whom it may concern:

Be it known that I, WILLIAM BRAMMER, a citizen of the United States, residing at Haverhill, in the county of Essex and State 5 of Massachusetts, have invented certain new and useful Improvements in Cement or Adhesive Applying Devices, of which the following is a specification.

My invention relates to machine methods 10 of supplying cement or other adhesives to tape or other material used in the manufacture of shoe uppers or for other purposes where an adhesive or binder is required.

The objects of my invention are, the elimination of the old hand method of applying cement or other adhesive to tape or other binder material, to provide a labor saving device accomplishing in a fraction of the time consumption that which has ordinarily 15 been a considerable factor in the process of manufacture, to insure a substantial saving in the amount of adhesive used for a given purpose, to provide an efficient means of mechanically applying adhesive to just 20 enough of the tape or binder surface so that when said tape or binder is applied under pressure none of the adhesive will ooze from beneath its edges, to provide an efficient automatic gage which regulates the amount 25 of adhesive used by the applying mechanism, and to provide other advantages and results some of which may be referred to in the following specification.

I attain the objects of my invention as 30 illustrated in the accompanying drawing, in which Figure 1 outlines a side view of my invention; Fig. 2 shows an end view; Fig. 3 shows an enlarged detailed view of my adhesive applying wheel; Fig. 4 shows 35 my lower tape or binder guide; Fig. 5 shows my upper tape or binder guide; Fig. 6 shows my intermediate tape or binder guide and automatic gage.

Similar letters refer to similar parts 40 throughout the several views.

Referring again to Fig. 1, A shows an adhesive reservoir in which the supply of cement or other adhesive is stored awaiting its consumption, in the operation of my improved device. The reservoir A is equipped 45 with an air tight cap B at its top, and an outlet C near its base. Over the outlet C is a sliding cap D, which may be raised or lowered at will, so as to open or close the outlet C. This outlet C opens into an open supply chamber E, in which revolves the

adhesive applying roll F, revolving on its axis G, which operates in the bearings H, one of which bearings, H, is secured to the outer wall of the open supply chamber E, 60 and the other of which is secured to the wall of the reservoir A. I shows a supporting upright projecting upward from the base J of my device. The upright I supports a tape or binder holding roll K upon 65 which is wound the material intended to be used in my device. L shows the tape or binder material as it unrolls from the holding roll K and passes downward onto the adhesive applying roll F, first passing 70 through the slots Z¹ in the retarding guide M which serve to give a tension to the tape or binder material. N shows my intermediate tape or binder guide through the slot Z² of which the tape or binder material 75 passes just prior to its contact with the applying roll F. O shows the lower tape or binder material guide through the slot Z of which the tape or binder material passes after it comes from the adhesive applying 80 roll F. P shows an upright post secured to my base J upon which revolves the roller Q intended for optional use in applying the tape or binder material to the article upon which it is to be attached. R shows a metallic guide located just to one side of the roller Q so as to act as a gage from or against which to operate. S shows my automatic gage and hinged or pivoted bracket, 85 upon which is rigidly secured the guide N, 90 and said bracket is fastened to the wall of the open supply chamber E at T, its outside prongs U which are relatively long, extend along the outer-sides of the applying roll F, and serve to retain the bracket in its 95 proper position, and the short prongs U' extend into the channels of the roll F to regulate the depth of the paste therein.

In Fig. 2, V shows a tension nut by which the bearing of the holding roll K is tight- 100 ened.

Fig. 3 shows that the circumference of the applying roll F is grooved by the channels W. X represents the outer circumference. It is these channels, W, in which the cement or other adhesive is carried from the bottom of the open supply chamber E to the top of the applying roll F where it contacts with the tape or binder material L.

Fig. 4 shows the detail of my lower tape 110 or binder guide. Y represents the rivets by means of which it is fastened to the side

of the open supply chamber E. Z shows the slot through which the tape or binder material passes as it comes off from the applying roll F.

5 In Fig. 5, Y¹ likewise show the rivets by means of which my upper tape or binder guide is fastened in its position to the side of the reservoir. Z¹ likewise represents the slots through which the tape or binder material passes as it comes from the roll K.

In Fig. 6, it will be noted, the prongs U fit in and about the circumference of the applying roll F and protrude into the channels W, so as to act as a scraper, eliminating 15 all cement or adhesives from the applying roll F, other than is contained in the bottom of the channels W.

In operation it will be understood that the cement or other adhesive used in my 20 device is supplied from the air tight reservoir A into the open supply chamber E, where the level of the adhesive is maintained at the top of the opening or outlet C. As the adhesive in the open supply 25 chamber E is used, it is automatically replaced by a fresh supply from the reservoir. It is of course necessary to close the opening C with the slide D before removing the air tight cap B to replenish the storage supply 30 of adhesive. The tape or binder material, L, as it comes from the roll K, first passes through the grooves Z¹ in the gage M, which acts as a brake or retarder, then passes through the intermediate gage end Z² up 35 onto and over the applying roll F, and then through the lower gage O at Z to any point where it is needed or desired. The tension caused by the gage M gives just enough pressure to the tape or binder material as 40 it passes over the applying roll F so that a portion of the material is drawn down into the channels W, where it contacts with and picks up the cement or other adhesive used, so that as the tape or binder material 45 passes off through Z of the gage O, the said adhesive is placed in parallel lines along its under surface. This parallel disposition of the adhesive material is particularly advantageous over and above any other 50 application heretofore used, for the reason that in applying the tape or binder material to the surface for which it is intended, the spread of the adhesive is just sufficient to bring it to the edge of the tape or binder 55 material. The quantity of adhesive for this purpose is easily regulated by the distance at which the scraper S is placed from the circumference of the applying roll F.

The scraper being pivoted, and the guide 60 N being fixed rigidly thereto, it is obvious that the greater the tension on the tape, the closer the scraper will be drawn to the roll F. In other words, the greater the tension on the tape the tighter it will bear down 65 on the grooved periphery of the roll F, and

consequently the intermediate portions of the tape will enter the channels W. At the same time owing to the pull on the tape, the guide N and scraper S will be pulled upwardly, so that the ends of the short 70 prongs will be close to the bottoms of the channels W, and the portions of the scraper between the bases of the short prongs will engage against the outer periphery of the roll F. Thus the scraper is automatically adjusted to and from the roll F by the tension placed upon the tape. The scraper with its tape guide is so pivoted with respect to the roll F, that when a normal tension is placed upon the tape, the portions between the 80 prongs will scrape easily over the outer periphery of the roll F, so that substantially no paste will be applied to the tape by the periphery of the roll, but when a slack tension is given the tape it will not 85 enter as deeply into the channels W, and the scraper will drop a slight degree, thereby allowing a greater depth of paste in the channels with which the slackened tape can contact, but not as intimately therewith as 90 when the tape is under its tightest tension. So that although the paste is deeper in the channels at this time, the contact of the tape therewith is lighter and consequently a lesser amount of paste is applied from the 95 channels, but this amount is slightly amplified by the addition of a slight quantity which will be applied by the periphery of the roll and which has been allowed to pass the scraper owing to its slight dropped position due to the slack tension on the tape. In any event the amount of paste applied is only sufficient to cover the surface of the tape without oozing beyond its edges, and always the preponderance of paste is applied by the channels in parallel lines. 100

Having thus described my invention what I claim as new and desire to secure by Letters Patent of the United States is:

1. In an adhesive applying device, a rotatable paste roller, tape-guides for directing the tape into engagement with said roller, and a scraper movable to and from the paste roller and which is automatically controlled to regulate the amount of paste 110 on the roller by the degree of pull given on the tape through one of said tape-guides. 115

2. In an adhesive applying device, a rotatable paste roller having a channeled periphery, tape-guides for directing the tape 120 into engagement with said roller, a scraper having prongs to engage in the channels of the roller to regulate the amount of paste in said channels, said scraper being movable to and from the roller and automatically controlled by the degree of pull given the tape through one of said tape-guides. 125

3. In an adhesive applying device, a rotatable paste roller, a scraper movable to and from the paste roller to regulate the 130

amount of paste on said roller, and a tape-guide fixed to said scraper, said scraper being automatically controlled by the degree of pull given the tape through said tape-guide.

4. In an adhesive applying device, a rotatable paste roller having a channelled periphery, a scraper movable to and from said roller to regulate the amount of paste thereon and provided with prongs to engage in the channels of the roller and side prongs to engage the sides of the roller, and a tape-guide fixed to said scraper, said scraper being automatically controlled by the degree of pull given the tape through said tape-guide.

5. In an adhesive applying device, a rotatable paste roller, a supply chamber for supplying paste to said roller, a scraper pivoted to the wall of said supply chamber and movable to and from the paste roller to regulate the amount of paste thereon, and a tape-guide carried by said scraper, said scraper being automatically controlled by the degree of pull given the tape through said tape-guide.

6. In an adhesive applying device, a rotatable paste roller, a scraper mounted to move to and from said paste roller to regulate the amount of paste on the roller, a

tape-retarding guide fixed to the device in advance of the paste roller and scraper, and a tape-guide carried by the scraper and positioned between said retarding-guide and the paste roller, the movements of said scraper being automatically controlled by the degree of pull given the tape through the guide on the scraper.

7. In an adhesive applying device, a rotatable paste roller, a scraper mounted to move to and from said paste roller to regulate the amount of paste on said roller, a tape retarding-guide fixed to the device in advance of the paste roller and scraper, said retarding-guide being formed with a pair of parallel slots having dividing bar therebetween around which the tape is drawn, and a tape-guide carried by the scraper and positioned between the retarding-guide and paste roller, the movements of said scraper being automatically controlled by the degree of pull given the tape through the guide on the scraper.

In testimony whereof I affix my signature in the presence of two witnesses.

WILLIAM BRAMMER.
